COMBINED CORN PLANTER AND CULTIVATOR.

No. 285,889.

Patented Oct. 2, 1883.

UNITED STATES PATENT OFFICE.

GEORGE W. GIFFARD, OF ODIN, KANSAS.

COMBINED CORN-PLANTER AND CULTIVATOR.

SPECIFICATION forming part of Letters Patent No. 285,889, dated October 2, 1883.

Application filed April 14, 1883. (No model.)

To all whom it may concern:

Be it known that I, GEORGE W. GIFFARD, a citizen of the United States, residing at Odin, in the county of Barton and State of Kansas, have invented a new and useful Combined Corn-Planter and Cultivator, of which the following is a specification, reference being had to the accompanying drawings.

This invention relates to combined corn-planters and cultivators; and it consists in certain improvements in the construction of the same, which will be hereinafter fully described, and particularly pointed out in the claims.

15 In the drawings hereto annexed, Figure 1 is a perspective view of my improved machine, showing the same rigged for planting corn. Fig. 2 is a longitudinal vertical sectional view of the same. Fig. 3 is a vertical transverse sectional view taken through the axle. Fig. 4 is a bottom plan view. Fig. 5 is a perspective view, showing the machine converted into a cultivator; and Figs. 6, 7, and 8 are detail views of detached parts of the machine.

25 The same letters refer to the same parts in all the figures.

A in the drawings designates an arched frame, to the sides or legs of which, BB, the forwardly-extending converging frame-pieces C C are secured. The lower ends of the legs B B are bent inwardly, forming brackets D D, above which the axle E is journaled in boxes F F, that are secured to the legs B by means of clips G. Upon the brackets D D, at the lower 35 ends of the legs B, are hinged blocks H, to the rear ends of which the cultivator-beams I are hinged in such a manner as to be capable of swinging in a horizontal plane. The said beams are of the ordinary construction, and are equipped with standards J and shovels K.

40 L is a beam hinged detachably between the front ends of the bars C C, and carrying at its rear end a standard, M, extending upwardly through a slot, N, in a lever, O, which is pivoted to a bracket, P, at the front end of bars C. Standard M is pivoted in the slot N by a transverse pin. The rear ends of the bars C are connected by a rock-shaft, Q, having an upwardly-projecting notched arm, R, which 45 extends upwardly through a slot, S, in the lever O. The latter is provided with a suitable spring catch or pawl, T, engaging the notches

in the arm R. By this mechanism the standard M, which carries at its lower end a furrow-opener, U, may be raised or lowered and 55 set at any desired elevation.

Secured to the under side of the rock-shaft Q is a bail or bracket, V, having hooks W, upon which the cultivator-beams, which are provided with loops X, may be hung, so as to 60 be temporarily raised from the ground.

The brackets D are connected with the bars C by forwardly-extending inclined braces Y.

Z are hooks hinged upon the brackets D, adjoining the braces Y and blocks H, and 65 serving for the attachment of the draft by means of rods A², extending rearwardly from the double-tree B². The latter is also connected detachably with the beam L by means of a vertical bolt, C².

70 D² is a bail or frame extending downwardly from the bars C C, and serving to support the seed-box or hopper E², which is supported directly above the axle E. Upon the latter is mounted a wheel or disk, F², the periphery of 75 which extends through a slot in the bottom of the seed-box, and is provided with a series of equidistant depressions forming the seed-cups G². The axle E is provided with a sprocket-wheel, H², the arms of which register with the 80 seed-cups.

To the under side of the frame D² is secured the seeding-tube I², which is provided with a hinged door, J², which is held closed by the action of a spring, K². The upper end of the 85 door J² has an outwardly-extending arm, L², adapted to be engaged by the sprocket-wheel H², which thus serves to open the said door and permit the seed to drop. In the front part of the bottom of the hopper is placed a 90 cut-off, which consists of a suitable casing, M², inclosing a flat spring, N², which bears upon the periphery of the seeding-wheel.

O² and P² are the wheels, the former of which is mounted loosely upon the axle. The wheel 95 P² is formed with a clutch, Q², which engages a clutch-collar, R², secured upon the axle, and with which it is normally held in contact by a spring, S², coiled upon the spindle between the wheel and a washer, T², at the end of the spindle. U² is a lever pivoted to a bracket, V², depending from one of the frame-bars C, and having a pivoted arm, W², provided with a collar, X², that rests against the inner end of 100

the hub of the wheel P^2 . The lever U^2 has a suitable spring pawl or catch, Y^2 , engaging a segmental ratchet, Z^2 , and which serves to retain the said lever in any position to which it 5 may be adjusted.

The operation of this part of my invention will be readily understood from the foregoing description, taken in connection with the drawings hereto annexed. When the wheel P^2 is 10 thrown into engagement with the axle, the latter is revolved, thus operating the seeding mechanism and dropping the corn at regular intervals, which are regulated by the sprocket-wheel. The wheel P^2 may be equipped with 15 markers and the machine used for check-rowing. The seed-wheel may also be removed, and another one, which has been shown in Fig. 6, substituted. The construction of this is the same, with the exception that it has a much 20 larger number of seed-cups. In this case a seed-tube is used without the hinged door, and the machine is thus adapted to sow in drills.

In order to convert the machine into a cultivator, I detach from the frame the axle, the 25 seed-box and tube, and their supporting-frame, the beam L , the lever for setting the said beam, and the lever U^2 and its attachments. To the sides B of the frame A , I then secure stub-axes A^3 B^3 by means of the clips G , which were 30 previously used for securing the axle. Upon these stub-axes the wheels are journaled. One of the stub-axes, B^3 , has a revolving clutch-collar, C^3 , to engage the clutch of the wheel P^2 , for the purpose of preventing anything 35 from catching in the said clutch and interfering with the operation of the machine. The latter is then ready to be used as a cultivator. For very young and tender corn I prefer to detach the front cultivator-shovels, and sub- 40 stitute for the same the knives or cutters D^3 , (shown in Fig. 8,) the uses and advantages of which are obvious.

This device or machine is simple and 45 convenient, as well as inexpensive, and it combines in one the seeder and cultivator, thus doing away with the necessity of providing separate machines. The seeding attachment is also capable of being used in combination with almost any ordinary cultivator-frame.

50 I claim as my invention and desire to secure by Letters Patent of the United States—

1. The combination of the arched frame, the axle journaled in boxes clipped detachably to the sides of said frame, the converging beams 55 secured to the upper ends of said sides, a bail

or bracket depending from the said beams, and the hopper and seeding-tube mounted upon the said bracket, substantially as set forth.

2. The combination of the arched frame having inturned brackets at its lower ends, the 60 cultivator-beams universally jointed to the said brackets, the converging frame-beams secured to the upper end of the frame, a beam pivoted between the front ends of the converging frame-beams, and having a vertical standard, a lever 65 connected to and operating said standard, a rock-shaft connecting the rear ends of the converging beams, a rack-bar secured to said rock-shaft and engaging a pawl or catch upon the adjusting-lever, and a bail secured upon the 70 under side of the rock-shaft and having hooks to support the cultivator-beams in a raised position, as set forth.

3. The combination of the arched frame having inturned brackets, as described, the converging frame-bars braced to said brackets, hooks hinged upon said brackets, the beam pivoted between the converging bars, the whiffletree secured upon said beam, and rods connecting the whiffletree with the hinged hooks, 75 substantially as set forth.

4. The combination of the arched frame, the axle journaled in boxes clipped detachably to said frame, the seed-wheel and sprocket-wheel upon said axle, the transporting-wheels 85 mounted loosely upon the axle, mechanism for connecting one of said wheels with the axle, the converging bars secured to the frame, a bracket secured to the same, the seed box and tube mounted upon said bracket, the cut-off 90 in the seed-box, a door hinged in the seed-tube and having an outwardly-projecting arm engaging the sprocket-wheel, and a spring arranged to keep the said door automatically closed, as set forth.

5. The combination of the frame, the axle having a stationary clutch, the wheel having a clutch, a spring interposed between said wheel and a washer upon the end of the spindle, a lever pivoted to the frame, and an arm pivoted upon said lever and having a collar bearing against the inner side of the hub of the wheel, as set forth.

In testimony that I claim the foregoing as my own I have hereto affixed my signature in 105 presence of two witnesses.

GEORGE WASHINGTON GIFFARD.
